(57) **CLAIM**

The ornamental design for a holder for ammunition magazine, as shown and described.

DESCRIPTION

FIG. 1 is a perspective view of my holder for ammunition magazine.

FIG. 2 is a side elevation view, the opposite side view being identical;

FIG. 3 is a top view thereof.

FIG. 4 is a bottom view thereof.

FIG. 5 is a rear view thereof.

FIG. 6 is a front view thereof.

FIG. 7 is a top view thereof; and,

FIG. 8 is a lengthwise cross sectional view of the holder, shown along line 8-8 of FIG. 7.
